UNITED STATES PATENT OFFICE.

GEORGE H. ALTBACH, OF BROOKLYN, NEW YORK, ASSIGNOR TO EAGLE LITES, INC., A CORPORATION OF NEW YORK.

DESIGN FOR A BRACKET PLATE FOR LIGHTING FIXTURES OR ANALOGOUS ARTICLE.

Application filed September 19, 1928. Serial No. 28,218. Term of patent 3½ years.

To all whom it may concern:

Be it known that I, GEORGE H. ALTBACH, a citizen of the United States, and a resident of 395 Schenectady Avenue, borough of Brooklyn, county of Kings, and State of New York, have invented a new, original, and ornamental Design for a Bracket Plate for Lighting Fixtures or Analogous Articles, of which the following is a specification, reference being had to the accompanying drawing, forming a part thereof.

In the drawing:

Figure 1 is a front elevational view of the back plate for lighting fixtures or analogous articles; and

Figure 2 is a diagrammatic edge view of the same.

I claim:

The ornamental design for a bracket plate for lighting fixtures or analogous article substantially as shown.

GEORGE H. ALTBACH.
